MOLDED PLASTIC BOTTLE CARRIER

Kenneth W. Bromley, Hobart, Ind., assignor to General American Transportation Corporation, a corporation of New York

Filed May 12, 1965, Ser. No. 85,240

Term of patent 14 years

(Cl. D58—26)

FIG. 1

FIG. 4

FIG. 5

FIG. 2**FIG. 3**FIG. 1 is a side elevational view of a molded plastic bottle carrier showing my new design, the opposite side being substantially the same in appearance;

FIG. 2 is an end elevational view thereof, the opposite end being substantially the same in appearance;

FIG. 3 is a top view thereof;

FIG. 4 is an enlarged vertical sectional view thereof taken along the line 4—4 in FIG. 1; and

FIG. 5 is another enlarged vertical sectional view thereof taken along the line 5—5 in FIG. 1.

I claim:

The ornamental design for a molded plastic bottle carrier, substantially as shown and described.
